(57) **CLAIM**

The ornamental design for an outdoor lantern, as shown and described.

DESCRIPTION

FIG. 1 is a perspective view of an outdoor lantern, showing my new design;

FIG. 2 is a front elevational view thereof all sides being identical;

FIG. 3 is a top plan view thereof; and,

FIG. 4 is a bottom plan view thereof.

The broken line showing of environmental structures in FIGS. 1-3 is for illustrative purposes only and forms no part of the claimed design.
